UNITED STATES PATENT OFFICE.

GEORGE S. HUNT, OF PASADENA, CALIFORNIA.

DESIGN FOR A COMBINED SWITCH PLATE AND SWITCH-OPERATING ELEMENT.

Application filed March 7, 1927. Serial No. 21,003. Term of patent 7 years.

To all whom it may concern:

Be it known that I, GEORGE S. HUNT, a citizen of the United States, residing in the city of Pasadena, Los Angeles County, California, have invented a new, original, and ornamental Design for Combined Switch Plate and Switch-Operating Element, of which the following is a specification, reference being had to the accompanying drawing, forming a part hereof. In the drawing,—

Figure 1 is a face view of the design in which the part shown in dotted outline is understood to be identical with that shown in solid black lines; and

Figure 2 is an edge or side view thereof.

I claim:

The ornamental design for a combined switch plate and switch operating element, substantially as shown.

GEORGE S. HUNT.
